UNITED STATES PATENT OFFICE.

ANDREW MORRISON, OF PITTSBURG, PENNSYLVANIA.

ROLLING FLANGED BARS.

SPECIFICATION forming part of Letters Patent No. 632,967, dated April 11, 1899.

Application filed November 5, 1898. Serial No. 695,544. (No model.)

To all whom it may concern:

Be it known that I, ANDREW MORRISON, of Pittsburgh, in the county of Allegheny and State of Pennsylvania, have invented a new and useful Improvement in Rolling Flanged Bars, of which the following is a full, clear, and exact description, reference being had to the accompanying drawings, forming part of this specification, in which—

10 Figures 1 and 2 are front elevations of rolls containing passes shaped in accordance with my invention.

In the drawings, 1, 2, and 3 represent the first successive passes in which a blank is formed, having side flanges *a a*, projecting at an angle to the body, and a body *b*, which is curved or bent in the same direction as the flanges. In the succeeding passes 4, 5, and 6 the plate and flanges are thinned in cross-section and the flanges are gradually brought to the right-angled position shown in pass 6, the body still retaining its curved or bent form. In the succeeding passes 7, 8, and 9 the body of the plate is flattened and the 25 plus metal is forced out laterally, so as to widen the plate and form side extensions which project beyond the flanges, the flanges being held in place and prevented from moving out during this widening process.

30 The flanges may, if desired, be moved in during the widening of the plate and may also be inset from the side edges before the widening of the plate.

The advantages of my invention result from the bowing or bending of the plate-body in 35 the direction of the flanges, the surplus metal being thus provided, which is forced out, so as to widen the plate beyond the flanges.

Many variations in the form and dimensions of the bar and its flanges may be made 40 without departing from my invention, since

I claim—

1. In the manufacture of flanged bars, rolls having passes arranged to form a bar having side flanges and a body bent or bowed in the 45 direction of the flanges, and passes arranged to flatten the bent or bowed portion and widen the plate beyond the flanges, while preventing the outward movement of the flanges; substantially as described. 50

2. The method of rolling flanged bars, consisting in forming a flanged bar having a body portion bent or bowed in the direction of the flanges, and then flattening the body portion and forcing the surplus metal outwardly to 55 form side extensions while preventing the moving out of the flanges; substantially as described.

In testimony whereof I have hereunto set my hand.

ANDREW MORRISON.
